UNITED STATES PATENT OFFICE

122,953

DESIGN FOR COMPOSITE TUCKED FABRIC OR THE LIKE

Mary Geller, Chicago, Ill., assignor to Doctor Dress
Co., Inc., Chicago, Ill., a corporation of Illinois

Application August 3, 1940, Serial No. 94,176

Term of patent 7 years

To all whom it may concern:

Be it known that Mary Geller, a citizen of the United States, residing at Chicago, Illinois, in the county of Cook and State of Illinois, has invented a new, original, and ornamental Design for Composite Tucked Fabric or the like, of which the following is a specification, reference being had to the accompanying drawing, forming part thereof.

I claim:

The ornamental design for composite tucked fabric or the like, substantially as shown.

MARY GELLER.
